LAMP BEZEL FOR AUTOMOBILES OR THE LIKE

Eugene Bordinat, Jr., Bloomfield Hills, Mich., assignor to
Ford Motor Company, Dearborn, Mich., a corpora-
tion of Delaware

Filed Oct. 5, 1961, Ser. No. 66,984

Term of patent 7 years

(Cl. D48—32)

FIG. 1 is a front elevational view of a lamp bezel for automobiles or the like, showing my new design;

FIG. 2 is a top plan view;

FIG. 3 is a side elevational view;

FIG. 4 is a rear elevational view;

FIGS. 5, 6 and 7 are sectional views taken substantially on the lines 5-5, 6-6 and 7-7, respectively, of FIG. 1; and

FIG. 8 is an enlarged fragmentary sectional view of

the ribbed surface shown in FIG. 5 as taken along line 5-5 of FIG. 1.

I claim:

The ornamental design for a lamp bezel for automobiles or the like, substantially as shown.
